UNITED STATES PATENT OFFICE.

ARNOLD PACYNA, OF EVANSTON, ILLINOIS, ASSIGNOR TO CHICAGO FOLDING BOX COMPANY, OF CHICAGO, ILLINOIS, A CORPORATION OF ILLINOIS.

MACHINE FOR MAKING DOUBLE-FACED CORRUGATED PAPER.

995,084.

Specification of Letters Patent. Patented June 13, 1911.

Application filed August 29, 1910. Serial No. 579,584.

To all whom it may concern:

Be it known that I, ARNOLD PACYNA, a citizen of the United States, residing at Evanston, in the county of Cook and State 5 of Illinois, have invented certain new and useful Improvements in Machines for Making Double-Faced Corrugated Paper, of which the following is a specification, reference being had therein to the accompanying 10 drawing.

My invention relates to machines for making double-faced corrugated paper, and in the present invention a strip of single-faced corrugated paper and a strip of plain lining or facing paper are fed into the machine, paste is applied to the crowns of the unlined side of the web, and the two strips are then brought together and passed through a suitable drier or heater to remove 20 the moisture and dry the paste, the material being moved through the drier or heater by means of a pair of endless open-mesh carriers, preferably of woven metallic fabric, to facilitate the removal of the moisture 25 and drying of the paste, and is then fed to a cutter which severs the web into suitable lengths or sheets.

The invention consists in the matters hereinafter described and then pointed out in 30 the appended claims.

In the accompanying drawings, which illustrate a practical embodiment of my present invention, Figure 1 is a side elevation showing the front end of a machine 35 having my invention for applying a liner sheet to a single-faced corrugated sheet to make double-faced corrugated sheets; Fig. 2 is a similar view of the rear end of the machine of Fig. 1 including the rear end of 40 the drier or heater, feed belts, and apron-drive; Fig. 3 is a top plan view of the parts of Fig. 1; Fig. 4 is a similar view of the parts of Fig. 2; Fig. 5 is a longitudinal sectional view of part of the drier; Fig. 6 is a 45 cross-sectional view of parts of the drier.

The same reference letters refer to the same or corresponding parts in the several views.

A strip of corrugated paper 10 provided 50 with a lining or facing 30 on one side, composing a single-faced corrugated web or sheet, is fed over a paste-applying roll 40 which is provided with paste from any suitable pan 41 to apply it to the crowns of the

unlined side of the web which is held in 55 contact therewith by a pressure roller 42. The second liner 43 is led from a suitable roll between a pair of pressure rolls 44 located at the entrance to a suitable heater and between which the corrugated web and second liner are passed for the purpose of attaching the latter to the exposed crowns of the former as shown in Fig. 1. The pressure rolls 44 are mounted in bearing boxes 45 adjustable on the frame by any suitable 60 means, as the well-known adjusting screws 46 having swivel-connections with the boxes and threaded engagement with the frame as is customary, for the purpose of graduating the distance between these rolls to vary the 65 thickness of the sheet or web as by crushing or flattening more or less the crowns of the web. This also increases the surface of the 70 crowns to receive the paste and consequently the sticking surface of the web. 75

The drier or heater as preferably constructed consists of an opposite pair of hollow castings or plates 47 and 48 suitably supported on the frame and spaced apart and between which the material passes, the 80 top plate preferably being adjustable toward and away from the lower plate by suitable means such as the screw bolts 49 adjustably connecting it to the frame. The 85 chambers of the castings or plates are connected to a suitable source of steam supply, and the upper casting 47 is provided at intervals along its lower face with a number of curved recesses 50 in each of which a roller 51 is mounted to revolve, the roller 90 being journaled at each end in suitable bearings in the casting and being hollow and perforated at intervals in its surface, one of its journals 52 being hollow and suitably connected to a pipe 53 passing through a suitable stuffing box in the casting and suitably connected to the pipe 54 of any suitable 95 exhaust apparatus (not shown) whereby air and moisture are drawn off. The rollers 51 are so journaled that they project slightly 100 below the plane of the lower face of the casting or plate in order to help overcome friction between the plate and an endless web-moving belt (hereinafter described) and so facilitate the progression of the web of 10 paper through the heater or drier. The lower plate 48 is provided in its upper face with a series of recesses 55 having perfo-

rated tops and containing a pipe 56 connected to the exhaust pipe 54 to draw off the air and moisture. The recesses in the plates are preferably out of alinement or staggered as shown in Fig. 5, thereby extending the drying action over practically the entire web or sheet in the drier.

The corrugated web is moved through the drier or heater by means of an oppositely arranged pair of endless belts 57 composed of open-mesh wire cloth and traveling over drums 58 on the frame of the heater with the contiguous or adjacent runs of the belts arranged as shown to receive the paper material there-between, the adjacent or operative runs of the belts being held engaged with the material by the pressure rollers 44 and by the opposite plates of the heater which when the machine is in operation are spaced a suitable distance apart to obtain this result. The belt-carriers are driven by any suitable means and preferably by a pair of endless aprons as shown in Figs. 2 and 5. Each apron is arranged within its corresponding carrier and is in open or skeleton form being composed of an opposite pair of chains 59 and connecting slats 60, the chains being mounted upon suitable pairs of sprockets 61 on shafts 62 one of which receives motion by means of a drive belt 63 from any suitable source of power and transmits it to a shaft of the other apron by gears 64. The return runs of the belts 57 pass over suitable ball-bearing carrier or idler rollers 65 arranged on the frame, the operative runs being frictionally engaged and driven by the aprons.

The carriers being made of open mesh the moisture is drawn through the meshes from the paper material by the exhaust, so that the carriers do not retard the drying of the paper but allow all moisture to be drawn off uniformly throughout the surface of the material and so prevents the latter from blistering.

I claim:—

1. In a device of the class described, a pair of oppositely disposed drying-plates, a pair of endless open-mesh carriers having their carrying runs between the plates, means to move the carriers to draw a corrugated web through the drier, the plates having a series of exhaust passages and connections from the passages to a suitable exhaust device.
2. In a device of the class described, a pair of oppositely disposed drying-plates, a pair of endless open-mesh metallic carriers having their carrying runs between the plates, means to move the carriers to draw a corrugated web through the drier, the plates having a series of exhaust passages connected to a suitable exhaust device, and a series of rollers in one of the plates bearing on the associated belt at the exhaust passages therein.

3. In a device of the class described, a pair of oppositely disposed drying-plates, a pair of endless open-mesh metallic belts having their carrying runs between the plates, endless traveling aprons to move the belts to draw a corrugated web through the drier, the plates having a series of exhaust passages and connections from the passages to a suitable exhaust device.

4. In a device of the class described, a pair of oppositely disposed drying-plates, a pair of endless open-mesh metallic belts having their carrying runs between the plates, means to move the belts to draw a corrugated web through the drier, one of the plates having a series of exhaust recesses, and a series of perforated hollow rollers in the recesses and connected to an exhaust device.

5. In a device of the class described, a pair of oppositely disposed drying-chambers, a pair of endless open-mesh metallic belts having their carrying runs between the chambers, endless-aprons to move the belts to draw a corrugated web through the space between the chambers, one of the chambers having a series of exhaust recesses, and a series of perforated hollow rollers in the recesses and provided with hollow journals extending through the chamber.

6. In a device of the class described, a pair of oppositely disposed drying-plates, a pair of endless carriers having their carrying runs between the plates, means to move the carriers to draw a corrugated web through the drier, the plates having a series of exhaust passages in staggered relation, and connections from the passages to a suitable exhaust device.

7. In a device of the class described, a pair of oppositely disposed drying-plates, a pair of endless carriers, having their carrying runs between the plates, means to move the carriers to draw a corrugated web through the drier, the plates having a series of exhaust passages arranged in staggered relation and connected to a suitable exhaust device, and a series of rollers in one of the plates bearing on the associated belt at the exhaust passages therein.

8. In a device of the class described, a pair of oppositely disposed drying-plates, a pair of endless open-mesh metallic belts having their carrying runs between the plates, endless traveling skeleton aprons to move the belts to draw a corrugated web through the drier, the plates having a series of exhaust passages and connections from the passages to a suitable exhaust device.

9. In a device of the class described, a pair of oppositely disposed drying-plates, a pair of endless open-mesh metallic belts having their carrying runs between the plates, endless traveling skeleton aprons to move the belts to draw a corrugated web through the drier, one of the plates having a series of

curved exhaust recesses, and a series of perforated hollow rollers in the recesses and connected to an exhaust device.

10. In a device of the class described, a pair of oppositely disposed drying-chambers, a pair of endless open-mesh metallic belts having their carrying runs between the chambers, endless skeleton aprons to move the belts to draw a corrugated web through the space between the chambers, one of the chambers having a series of exhaust recesses,
- a series of perforated hollow rollers in the recesses and provided with hollow journals extending through the chamber, the other chamber having exhaust recesses intermediate the other recesses. 15

In testimony whereof I affix my signature in presence of two witnesses.

ARNOLD PACYNA.
